UNITED STATES PATENT OFFICE.

WILLIAM A. PIKE, OF BROOKLYN, ASSIGNOR TO HARD & PARSONS, OF NEW YORK, N. Y.

DESIGN FOR THE ORNAMENTATION OF PAPER.

SPECIFICATION forming part of Design No. 18,185, dated March 13, 1888.

Application filed February 13, 1888. Serial No. 263,906. Term of patent 7 years.

To all whom it may concern:

Be it known that I, WILLIAM A. PIKE, a citizen of the United States, residing at Brooklyn, in the county of Kings and State of New York, have invented a new, original, and ornamental Design for a Water-Mark for Paper; and I do declare the following to be a full, clear, and exact description of the design, such as will enable others skilled in the art to which it appertains to make and use the same, reference being had to the accompanying drawing, and to the letters and figures marked thereon, which form part of this specification.

My design is intended for the ornamentation of paper as a water-mark; and it consists of a series of curved lines grouped together and presenting to the eye the conventionalized outlines of three-leaved and four-leaved clover. In the accompanying drawing I have designated each 20 four-leaved clover by a numeral and each three-leaved clover by a lower-case letter.

The group composed of the clover 1, *a*, and *o* is at the upper left-hand corner of the design. It consists of the elements named, the stems of 25 *o* and *a* crossing each other to the right of the group and two of the leaves of *o* passing above one leaf each of 1 and *a*, the leaf 1 having its stem hanging downward. To the right of this group is the clover 2, having its stem tangent 30 to that leaf of *a* which is farthest to the right.

Below and to the right of the group last described is the group composed of the clover *b*, 35 5, *d*, *c*, *g*, and 4, in which the leaf of *b* farthest to the left and the uppermost leaf of 5, the lowermost leaf of 5 and the stem of *d*, the leaf of *d* farthest to the left and the stem of *c*, and the lowermost leaf of *c* and the stem of *g* are tangent to each other, while the stem of *g* terminates in the periphery of one of the leaves of 40 4. In this group, also, the stems of 4 and *c* hang downward, those of 5 and *b* extend to the left, and that of *d* extends to the right. The lowermost leaf of *g* is tangent to that leaf of *f* which is farthest to the right, and the lowermost leaf of *d* is tangent to one of the leaves of 45 8, *f* and 8 not being considered in this group. To the left of 4 and the right of 5 and 8 is the leaf 3, with depending stem.

Below the group last described are two others, the former composed of the clover 8, 7, 9, 50 10, *i*, 11, and *h*, and the latter, to the left of the

former, composed of the clover *f*, *e*, and 6. In the former group the lowermost leaf of 8 overlaps one of the leaves of 9 and its stem is tangent to another, the lowermost leaf of 7 and the leaf of *i* farthest to the left are overlapped by two of the leaves of 10, the uppermost leaf of *i* and the lowermost leaf of 9 are tangent to each other, the stems of 10 and *i* terminate in the stem of 7, which itself terminates in the periphery of that one of the leaves of 9 which is tangent to the stem of 8, the leaf of *i* farthest to the right overlaps the leaf of 11 farthest to the left, while the uppermost leaf of 11 and that leaf of *h* farthest to the left are tangent to each other, the uppermost leaf of *h* is tangent to one of the leaves of *e*, the stems of 11 and *h* cross each other, and the stem of *j* terminates in the periphery of one of the leaves of 10 and that of *h* in the stem of 9. In the latter group 70 the two leaves of 6 which extend farthest upward and to the left overlap in each case one of the leaves of *f* and *e*, respectively, while one of the leaves of *e* is tangent to the uppermost leaf of *h*, and the uppermost leaf of 14 and the lowermost leaf of 6 are also tangent to each other. The stems of *f*, *e*, and 6 all extend downward.

Directly below the group last described is the group composed of the clover 14, 12, 13, 80 17, and *n*, in which one of the leaves of 12 overlaps a leaf of 13, and another is tangent to another leaf of 13, 12 being to the left of 13. That leaf of 14 which is farthest to the left is tangent to that one of 13 which is partially 85 concealed by one of the leaves of 12, while the stem of 14 terminates in the periphery of one of the leaves of 13 and that of *n* in one of the leaves of 17, the uppermost and lowermost leaves of 17 being tangent to leaves of 13 and 90 *n*, 14 being above 13, 12 to the left of it, and 17 below it, *n* being below and to the left of 17. To the left of this group is the clover 16, which has its leaf farthest to the left tangent to the lowermost leaf of *k*. To the right of this last 95 group is the one composed of the clover *j*, 15, *k*, 16, *l*, *m*, 18, 19, 20, and 21. In this group one of the leaves of 15 conceals that leaf of *j* which is farthest to the right, the leaf of 20 farthest to the right conceals one of the leaves 100 of 21, and two of the leaves of 18 conceal one of the leaves of 19. The stem of 20 is tangent

W. A. Pike

to one of the leaves of *m*, that of *l* to one of the leaves of *j*, and the lowermost leaf of 21 to the stem of *b*, heretofore described. One of the leaves of 16 is tangent to the lowermost leaf of 5 *k*. That leaf of the latter which is farthest to the left is tangent to that one of 15 which is farthest to the right. The two lowest leaves each of 15 and *j* are tangent to each other, as are that leaf of *m* farthest to the left and that 10 one of *l* farthest to the right, and the uppermost leaf of 18 and the lowermost leaf of *l*. The stem of 19 terminates in the periphery of 20, that of 15 in the periphery of *m*, and that 15 of 18 in the stem of *o*. Below this last-named group the pattern repeats itself indefinitely.

What I claim as new is—

The design for the ornamentation of paper herein shown and described, consisting of the representations of the outlines of four-leaved clovers, as 1, 2, 3, 4, 5, 6, 7, 8, 9, 10, 11, 12, 13, 20 14, 15, 16, 17, 18, 19, 20, and 21, in combination with those of three-leaved clovers, as *a*, *b*, *c*, *d*, *e*, *f*, *g*, *h*, *i*, *j*, *k*, *l*, *m*, *n*, and *o*.

In testimony whereof I affix my signature in presence of two witnesses.

WILLIAM A. PIKE.
